DESIGN FOR A BOTTLE

Kit C. Love, Muskogee, Okla.

Application June 22, 1939, Serial No. 85,633

Term of patent 14 years

To all whom it may concern:

Be it known that I, Kit C. Love, a citizen of the United States, residing at the city of Muskogee, in the county of Muskogee and State of Oklahoma, have invented a new, original, and ornamental Design for Bottles, of which the following is a specification, reference being had to the accompanying drawing, forming part thereof.

The figure is a side view in elevation of a bottle, showing my new design. The bottle is round and the design is identical when viewed from the side opposite to that shown.

I claim:

The ornamental design for a bottle, as shown and described.

KIT C. LOVE.
